UNITED STATES PATENT OFFICE.

CHARLES C. ADAMS, OF CHARLOTTE, NORTH CAROLINA.

INTEREST-INDICATOR.

SPECIFICATION forming part of Letters Patent No. 622,098, dated March 28, 1899.

Application filed October 5, 1898. Serial No. 692,663. (No model.)

To all whom it may concern:

Be it known that I, CHARLES C. ADAMS, a citizen of the United States, residing at Charlotte, in the county of Mecklenburg and State 5 of North Carolina, have invented a new and useful Improvement in Interest-Indicators, of which the following is a specification.

My invention is an improvement in interest-indicators seeking to provide a simple construction whereby the depression of a key corresponding to the principal will operate to bring to proper adjustment figures representing the interest upon such principal for a series of periods, so the operator can readily 15 determine at a glance the amount of the interest upon such sum for the desired period.

The invention consists in certain novel constructions and combinations of parts, as will be hereinafter described, and pointed out in 20 the claims.

In the drawings, Figure 1 is a perspective view of my machine. Fig. 2 is a top plan view thereof, partly broken away. Fig. 3 is a vertical longitudinal section of the machine. 25 Figs. 4 and 5 are cross-sections on about lines 4 4 and 5 5 of Fig. 3. Fig. 6 shows a portion of the indicator-roller in side view and in section. Fig. 7 is a side view of a portion of the machine, showing the opposite side from that 30 shown in Fig. 1; and Fig. 8 is a detail view showing a portion of one of the rods and the toothed wheel meshed therewith.

The casing may be of any desired form or material, being in the construction shown 35 made with its top having a flat portion at A and an inclined portion A', the former having openings a, which expose the indicating-rolls B, presently described, and are provided with adjacent suitably-inscribed lists of 40 periods ranging from days and months up to years, these lists being close to the edge of the opening a to register with the list of amounts upon the indicating-roller exposed through such opening. In the operation of 45 the construction the indicating-roller is properly turned to bring in register with the opening a the list of amounts of interest upon the desired amount for the periods indicated alongside the opening a, the amount of the 50 calculated interest registering with its corresponding period alongside the opening a. The rollers B are preferably made polygonal,

having upon their several faces lists of interest amounts C, each list being secured to the proper face b of the roller B, and it is preferred to secure the said lists C removably to the roller (it may be by screws C' or other suitable manner) to permit one set of lists C to be removed and another applied. This is useful when it is desired to change the indicator from, say, four per cent., which is the rate calculated in the construction shown, to any other rate, such change only necessitating the removal of one set of lists from the roller B and the application of others at the 65 desired rate of interest instead. To avoid any confusion, I usually inscribe on each list at C² the rate of interest and the amount upon which interest is calculated to secure the result below, the amount being, say, ten dollars and the interest four per cent., as will be understood from the accompanying illustration. By the described construction it will be seen that if the roller be turned to bring its interest-list—say, for instance, calculated 70 at ten dollars—such list will indicate, in connection with the period-list on the case, the amount of interest for any desired period within the range of the indicator.

In order to operate the roller B to secure the 80 desired result, I provide means for turning it variable distances corresponding to the amount upon which interest is desired and so adjust such turning devices that the device corresponding to ten dollars will bring 85 the ten-dollar interest-list into register with the opening a, while the device corresponding to fifteen dollars will bring the fifteen-dollar interest-list into such register, and so on throughout the apparatus. To increase the 90 range of the machine, I prefer to provide several rollers B and operating devices in connection therewith; but as the devices used in connection with the several rollers are alike the description of one may answer for all. As 95 shown in the drawings, the roller B is provided with a long toothed wheel or roller D, which is meshed by teeth upon key-rods E, which rise above the inclined portion of the case and are provided with suitable heads or 100 buttons E'. The teeth upon these rods E or the extent of their movement, or both, are regulated according to the amount to which the particular key corresponds, the one-dollar key

being designed to move the roller B one step—that is, to bring its first interest-list into register with the opening *a*—the two-dollar key to bring the second interest-list into such register, and so on; but it should be understood that the specific relation between the interest-lists may be varied, the object being to turn the roll B by each of its operating-keys the distance necessary to bring the corresponding interest-list into register with the opening *a*. The key-rods E are suitably guided in bars F and F', and at the lower end of the teeth on each bar E', I provide a long tooth E², which is struck by a long tooth D' 15 on the roller D as such roller is returned to cipher position, such long tooth operating when so returned to push the bar E up out of mesh with the roller D in position to be caught by a spring-latch G, operating on a 20 projection g on the key-rod, such latch G operating as a friction or spring latch to hold the key-rod up and yet permit it to be pressed downward when desired to operate in the manner described.

25 To accurately adjust the movement of the key-rods, I provide adjustable stops H therefor in the form of screws turning through a suitable bearing H', supported in the casing and adapted to be adjusted to accurately stop 30 the key-rods in position to secure a registration of the proper interest-list with the opening *a* of the case.

In connection with each of the rollers D, I provide a toothed bar I, which meshes with 35 the corresponding roller and is arranged at its lower end for engagement by a bar J, the bar I being preferably provided at its lower end with a roller i, to be engaged by the bar J. This bar J is a part of the device for returning the rollers to the starting-point and 40 is supported on the swinging arms J', whose shaft J² is provided outside the machine with a suitable handle J³, by which the bar J may be operated to move the toothed bar I up to 45 return the roller B to the starting-point. The bar J extends beneath the several bars I, and it will be understood that as any one of the rollers B is operated by any of its keys the toothed bar I by its meshing with the toothed 50 roller D will be moved downward a distance corresponding to the movement given to said roller D, so the said bar I when moved upward to its starting-point will properly readjust the roller D and its attached roller B to 55 the starting-point.

In connection with the openings *a* in the case and the period-lists alongside said opening and the interest-lists on the rollers I prefer to provide a sight-guide for convenience 60 and accuracy in reading the amount. This sight-line consists of a frame K, which extends over the top of the case above the openings *a* and is provided with a narrow opening K', sufficiently large to expose any one of the registered period-lists and interest-lists. This frame K slides upon the case and is provided with a clamp K² for binding it in any

position to which it may be set. In this connection the plate K has at one end a depending wing K³, which hooks at K⁴ under a bar 70 L, extending alongside the case, the clamp-sections K⁵ being pivoted at K⁵ to the wing K³, being meshed with each other at K⁶ and having the cams K⁷, which in one position of the clamp-sections K⁵ bind against the rod L 75 and lock the frame K in such position, while in the other adjustment of the clamp-sections K⁵ the cams K⁷ are freed from the bar L, and the frame K may be slid readily along the case of the machine. 80

Having thus described my invention, what I claim, and desire to secure by Letters Patent, is—

1. In an apparatus substantially as described, the combination of the roller, the toothed roller or wheel connected therewith and having a long tooth, the key-rods having teeth meshing with said toothed roller and a long tooth co-operating with that of said roller, and arranged to be engaged thereby to return the key-rod to starting-point and means for detaining the key-rod at such point, as set forth. 85

2. The combination with the roller having the long-toothed wheel of the several key-rods meshing with said rollers and the spring-latches engaging said rods and operating as a detent to retain the same out of engagement with the toothed wheel, substantially as set forth. 95

3. An apparatus substantially as described comprising the casing having sight-openings, and adjacent thereto the period or time lists, the rollers beneath said openings and having the interest-lists registering with the period-lists of the casing, the toothed wheels extended from the roller, and the rods meshed with said toothed wheels, substantially as set forth. 105

4. In an apparatus substantially as described, the combination with the casing and the indicating devices of the sight-guide frame movable over the casing and registering with the indicating devices, and clamping means whereby the said sight-guide frame may be secured in any desired adjustment, substantially as set forth. 110

5. In an apparatus, substantially as described, the combination of the case or frame, the indicating-rollers, and means for operating the same, the sight-guide frame having at one end a hook-flange, a bar on the case engaged by such flange and the clamp-sections pivoted to the flange and having the cams engaging the bar on the case, substantially as set forth. 120

6. In an apparatus substantially as described, the combination of the roller and its toothed wheel, the key-bars toothed and meshing with said wheel, the wheel-returning bar meshing with the toothed wheel, and the lever having a bar engaging with and operating said toothed returning-bar, substantially as set forth. 130

7. The combination in an apparatus substantially as described, of the indicating-rollers having the toothed wheels, the key-rods meshed with said wheels, devices for holding said rods normally out of mesh with said wheels, the toothed returning-bars meshed with the toothed wheels, the bar extending beneath and engaging the several returning-
5 bars whereby to operate the same and having the swinging arms, and the handle or lever, to substantially as set forth.
